CLAIM

The ornamental design for an attendant module, as shown and described.

DESCRIPTION

FIG. 1 is a front, top and right side perspective view of an attendant module showing our new design;

FIG. 2 is a front elevation view thereof;

FIG. 3 is a top plan view thereof;

FIG. 4 is a right side elevation view thereof;

FIG. 5 is a left side elevation view thereof; and,

FIG. 6 is a bottom plan view thereof.

The broken line portion of FIG. 4 is included to show unclaimed internal subject matter only and forms no part of the claimed design.
